US00D979240S

(12) United States Design Patent (10) Patent No.: US D979,240 S
(45) Date of Patent: * Feb. 28, 2023

(54) WALLET

(71) Applicant: Dango Products, LLC, Portola Valley, CA (US)

(72) Inventors: Thuan Tran, Santa Clara, CA (US); Charlie Carroll, Palo Alto, CA (US); Binh Tran, Santa Clara, CA (US)

(73) Assignee: Dango Products, LLC, Portola Valley, CA (US)

() Term: 15 Years

(21) Appl. No.: 29/778,443

(22) Filed: Apr. 13, 2021

(57) CLAIM

The ornamental design for a wallet, as shown and described.

DESCRIPTION

FIG. 1 is a front, first side, and bottom perspective view of a wallet embodying the new design;

FIG. 2 is a back, first side, and top perspective view thereof;

FIG. 3 is a front view thereof;

FIG. 4 is a back view thereof;

FIG. 5 is a top view thereof;

FIG. 6 is a bottom view thereof;

FIG. 7 is a first side view thereof; and,

FIG. 8 is a second side view thereof.

The evenly dashed broken lines on claimed surfaces depict stitching and form no part of the claimed design.

1 Claim, 8 Drawing Sheets
